2,141,727

VALVE FOR PNEUMATIC TOOLS

Fred M. Slater, Phillipsburg, N. J., assignor to
 Ingersoll-Rand Company, Jersey City, N. J.,
 a corporation of New Jersey

Application July 13, 1936, Serial No. 90,355

2 Claims. (Cl. 121—19)

This invention relates to pneumatic tools, and more particularly to a distributing valve for pneumatic tools of the hammer type.

One object of the invention is to obtain a quick and positive action of the valve and, therefore, a rapid reciprocatory movement of the percussive element of the tool.

Other objects will be in part obvious and in part pointed out hereinafter.

In the drawing illustrating the invention and in which similar reference numerals refer to similar parts,

Figure 1 is an elevation, in section, of a pneumatic tool equipped with a valve constructed in accordance with the practice of the invention and showing the valve in position to supply pressure fluid behind the piston for driving it on its working stroke,

Figure 2 is a view similar to Figure 1 showing the valve in the other limiting position, and

Figure 3 is a transverse view taken through Figure 1 on the line 3—3.

Referring more particularly to the drawing, the invention is shown embodied in a pneumatic tool 29 comprising a cylinder 21 having a piston chamber 22 to accommodate a reciprocating hammer piston 23 which controls an exhaust port 19 and actuates a working implement 24.

The piston 23 is of the differential type having a head 25 and a stem 26, the latter extending slidably through a front cylinder washer 27 serving as a closure for that end of the piston chamber 22.

The working implement 24 extends into a front head 28 forming the front casing part of the pneumatic tool. The front head serves as a housing for a chuck 29 which guides the working implement 24 and wherewith the working implement is slidably interlocked. Within the chuck 29 are ribs 30 extending into grooves 31 in the stem 26 of the piston to slidably interlock the piston to the chuck.

Seated on the rear end of the cylinder 21 is a cylinder extension 32 which in turn serves as a seat for a back head 33 forming the rearmost casing part of the tool 28. The back head 33 may, as is customary, serve as a housing for the head (not shown) of a rifle bar 34 which extends into the piston chamber 22 and is interlocked with the piston 23 in a well known manner to cause rotary movement of the piston during one of its strokes.

In accordance with the practice of the invention, the back head 33 is provided with a boss 35 that extends into a bore 36 in the cylinder

extension 32. The boss is recessed in its free end to form a valve chamber 37 comprising, in the present instance, a front enlarged portion 38 and a rear reduced portion 39.

Intermediate the ends of the reduced portion 39 of the valve chamber is an annular groove 40 which communicates with the enlarged portion 38 through an annular passage 41 of which the rifle bar constitutes the inner bounding surface. From the annular groove 40 leads an inlet passage 10 42 that opens into the front end of the piston chamber to convey pressure fluid thereto for actuating the piston rearwardly. The admission of pressure fluid to the rear end of the piston chamber is effected through a passage 43 in a wall 44 15 15 which is an integral portion of the cylinder extension 32 and serves as a closure for the rear end of the piston chamber.

In the rearward surface of the wall 44 is an annular groove 45 which lies outside of the plane 20 of the valve chamber to serve as a supply reservoir for pressure fluid. Pressure fluid is admitted into the groove 45 through a passage or passages 46 in the extension 35 leading from an annular supply chamber 47 in the periphery of the boss 25 35, and the admission of pressure fluid into the tool 29 from a suitable source of supply (not shown) is controlled by a throttle valve 48 housed, in the present instance, in the cylinder extension 32.

Arranged within the valve chamber 37 is a valve 49 of the reciprocating type for distributing the pressure fluid to the end of the piston chamber. The valve comprises a flange 50 which lies within the enlarged portion 38 of the valve chamber 35 and an integral hollow stem 51 which lies within the reduced portion 39. The periphery of the stem 51 seats slidably upon the wall of the reduced portion 39 and the bore 52 in the valve is sufficiently larger than the rifle bar, which the 40 extension 51 encircles, to at all times assure free communication between the rear ends of the enlarged portion 38 and the piston chamber.

Likewise, the periphery of the flange 50 seats slidably on the wall of the enlarged portion 38 45 to assist in guiding the valve. In the periphery of the flange 50 are a series of notches 53 through which pressure fluid flows from the groove 45 into and through the rear end of the enlarged portion 38 thence through the channels connecting said 50 enlarged portion with the front end of the piston chamber.

On the opposed surfaces of the boss 35 and the wall 44 are raised seating surfaces 54 and 55, respectively, for the adjacent surfaces of the 55

flange 50, and the portions of the flange 50 lying outside of the seating surfaces 54 and 55 constitute pressure surfaces 56 and 57 which are constantly exposed to pressure fluid tending to assist in throwing the valve from one limiting position to another. The diameter of the seating surface 54 is preferably smaller than that of the seating surface 55 and, in consequence, the pressure surface 56 is of greater area than the pressure surface 57.

The portion of the front end of the valve lying inside of the seating surface 55 constitutes an actuating surface 58 which is in constant communication with the rear end of the piston chamber through the passage 43 and is, therefore, intermittently subjected to the compression in the rear end of the piston chamber to assist in throwing the valve rearwardly. The valve is, moreover, provided with an opposed actuating surface 59 on the rear end of the flange 50 and lying between the seating surface 56 and the extension 51.

The operation of the device is as follows: With the valve 49 and the piston 23 in the positions illustrated in Figure 1 pressure fluid flows from the groove 45 through the space between the flange 50 and the seating surface 55, thence through the passage 43 into the rear end of the piston chamber 22 to actuate the piston 23 forwardly against the working implement. During the forward movement of the piston, and after the piston has closed the exhaust port 19, the air in the front end of the piston chamber is compressed and expelled through the passage 42 into the annular groove 40 and the passage 41 and acts upon the actuating surface 59. When the rear end of the piston uncovers the exhaust port 19 pressure fluid used for actuating the piston exhausts to the atmosphere, and the compression acting against the surface 59, together with the pressure fluid acting against the pressure surface 56 will then immediately throw the valve forwardly against the seating surface 55.

In the new position of the valve pressure fluid flows from the groove 45 through the notches 53 and the rear end of the enlarged portion 38 of the valve chamber, thence through the passage 41, the groove 45 and the inlet passage 42 into the front end of the piston chamber to return the piston to its initial position. During its rearward or rising movement the piston again covers the exhaust port 19. The air in the rear end of the piston chamber 22 is then compressed and will act against the actuating surface 58.

As the piston nears its rearward stroke it un-

covers the exhaust port 19 and the pressure fluid used for driving the piston rearwardly will escape to the atmosphere. In consequence, there will be an abrupt drop in the pressure value of the fluid acting against the rear surface of the flange 50. The compression acting against the surface 58 will then act to throw the valve rearwardly to its initial position. Such compression is assisted, however, by the force of suction of the pressure fluid flowing through the notches 53 and exerting a drag on the valve and also by the pressure fluid acting against the pressure surface 57.

I claim:

1. In a pneumatic tool, the combination of a cylinder and a piston therein, a valve chest having a valve chamber and front and rear inlet passages for supplying pressure fluid to the cylinder, a valve in the valve chamber, a flange on the valve slidably engaging the chest controlling the flow of pressure fluid to the inlet passages, said flange having channels in its periphery through which pressure fluid flows to one inlet passage, said channels having their surfaces subjected to the suction of the pressure fluid for throwing the valve in one direction, opposed actuating surfaces on the valve, one of said actuating surfaces being intermittently subjected to compression from the cylinder to assist the force of suction in throwing the valve and another actuating surface being intermittently subjected to compression from the cylinder to throw the valve in an opposite direction, and opposed differential pressure surfaces on the valve constantly exposed to pressure fluid to assist in throwing the valve.

2. In a pneumatic tool, the combination of a cylinder and a piston therein, a pair of casing parts defining a valve chamber, opposed seating surfaces on the casing parts, front and rear inlet passages for conveying pressure fluid from the valve chamber to the front and rear ends of the cylinder, a valve in the valve chamber, a single flange on the valve slidably engaging the valve chest and cooperating with the seating surfaces to control the flow of pressure fluid to the inlet passages, opposed actuating surfaces on the flange intermittently subjected to compression from the cylinder for throwing the valve, and channels in the periphery of the flange through which pressure fluid flows to only the front inlet passage and being subjected to the suction of the pressure fluid to assist in throwing the valve for cutting off the flow of pressure fluid to the front inlet passage.

FRED M. SLATER.
